CONVEYER POLE FOR DRYING MACHINES
AND THE LIKE

Thomas Allsop and Walter W. Sibson, Philadelphia, Pa., assignors to The Philadelphia Drying Machinery Company, Philadelphia, Pa., a corporation of Pennsylvania

Application April 11, 1934, Serial No. 720,028

11 Claims. (Cl. 34—20)

This invention relates to conveyer poles useful more particularly in connection with textile drying machines and the like wherein continuous fabric or sheet material is supported in festoons 5 incident to progression through the machines for drying or other treatment.

The general practice heretofore has been to construct such conveyer poles with axial core members usually of tubing or piping, and with 10 split coverings or jackets of wood consisting of two half-round one-piece sections of a length equal substantially to that of the core members, which sections were secured to said core members either by transverse fastening devices, or by recessed circumferential bands of wire or tape metal at suitable intervals lengthwise of the pole. Due to twists and other irregularities or changes 15 in the direction in the grain of the wood, these relatively long half-round jacket sections invariably become warped, distorted and misshapen and part at the joints, or they fracture and splinter in responding to expansion and contraction under the influence of moisture and heat, thereby presenting irregular surfaces for contact 20 with the fabrics or sheets and causing streaking or other damage to them. Renewal of the deteriorated jackets was obviously expensive in that it entailed complete replacement of them.

In the main, our invention is directed toward 30 overcoming the several drawbacks which have just been pointed out. This desideratum we secure in practice by constructing the jacketing of the poles from relatively short-length cylindric sections, which, when assembled on the axial core 35 member and abutted end to end, provide a continuous flush and smooth surface for contact with the fabric. Due to being tubular in form, the jacket sections are inherently strong and therefore highly resistive to fracture or distortion under the action of moisture or heat. Another advantage of our invention is that any sections 40 which have become deteriorated after long continued service can be readily replaced without necessitating renewal of the jacketing as a whole.

Another aim of our invention is to provide for 45 maintaining the jacket sections of the poles assembled in closely abutted relation on the core members and at the same time permit lengthwise expansion and contraction of the jacket as 50 required.

Our invention is further directed toward improved construction of conveyer poles of the kind referred to wherein insulating air spaces are provided within the poles along the metallic core 55 members with a view toward preventing direct

conduction of heat from said core member to the jacketing and thereby reducing the deteriorating effect caused by extremes of temperature.

Still other objects and attendant advantages will be manifest from the following detailed description of the accompanying drawing.

Fig. I is a broken-out view, partly in elevation and partly in axial section, of a conveyer pole conveniently showing one embodiment of our invention.

Fig. II is a cross sectional view taken as indicated by the arrows II—II in Fig. I.

Figs. III and IV are fragmentary views corresponding to Fig. I of modified forms of the jacketed type of conveyer pole.

With detailed reference first to the embodiment of our invention delineated in Figs. I and II, the metallic core member of the pole is indicated at 15, while the non-metallic jacketing of said pole is comprehensively designated by the numeral 16. 20 As ordinarily, the core member 15 is formed from tubing or piping, and, as shown, said core member projects beyond the jacketing 16 at opposite ends of the pole to afford trunnions capable of being rotatively engaged in lateral bearing sockets on spaced links of laterally-spaced conveyer chains, not illustrated. The pole may also be used with conveyer chains having lateral studs to engage the hollows of the core member 15 at opposite ends. There are thus two ways in 25 which the pole may receive journal support for free rotation on the conveyer chains.

In accordance with our invention, the jacketing 16 is made up of a number of relatively short length tubular cylindric unitary sections 17, 18 35 and 19 which are preferably fashioned from wood, although fiber or other non-metallic material may be employed in their construction if expedient. The internal diameter of the jacket sections 17—19, it will be particularly observed, 40 is larger than the external diameter of the core member 15 with resultant provision of circumferential air spaces 20 internally of the pole within the confines of said sections and around said core member. The ends of the tubular 45 jacket sections 17—19 are axially recessed as at 21 and 22. The recesses 21 at the junctures between adjacent jacket sections 17, 18 and 18, 19 jointly form annular hollows to snugly accommodate collars 23 of a corresponding diameter, said 50 collars being free to shift on the core member 15, and, like the jacket sections, preferably fashioned from wood or fiber. The recesses 21 are 55 amply deep so that sufficient clearance is afforded to permit direct abutment of the contiguous

square cut ends of adjacent jacket sections 17, 18 and 19, as shown in Fig. I. The function of the collars 23 is to support and maintain the jacket sections 17-19 in true coaxial relation 5 with the core member 15. The position of the jacketing 16 on the core member 15 is determined by a metallic collar 24 secured, with provision for adjustment, to said core member somewhat inward of its left hand end (as considered in Fig. I), by means of a set screw 25. The collar 24 is illustrated as having teeth 26 for coaction with suitable racks along the path of the conveyer and consequent impartation of rotary movement to the pole in a known manner. As 10 shown, the collar 24 is further provided at its inner side with an axial boss 27 to fit the recess 21 in the contiguous end of the jacket section 17. The axial recess 22 in the jacket section 19 at the opposite end of the pole is considerably 15 deeper than the recesses 21, and, as shown, houses a helical spring 28 which is in compression between the shoulder 29 of the recess 22 and another collar 30 adjustably set on the core member 15. With the described arrangement it will 20 be apparent that the spring 28 serves to maintain the jacket sections 17-19 in close end contact, one with another, and the jacket 16, as a whole, in firm end contact with the toothed collar 24, while allowing endwise expansion of the sections 25 under the action of moisture and heat. The spacing collars 23 may be solid in cross section, or they may be internally notched or longitudinally grooved as at 31 in Fig. II for continuous communication between the circumferential air-spaces 20 within the sections 17-19.

By virtue of the sectional construction of the jacket 16, the strains induced by action of moisture and heat will be locally confined and not transmitted throughout the length of the jacket 40 16 as was the case with conveyer poles constructed as heretofore. Furthermore, due to the integral formation of the jacket sections 17-19 as complete tubes (as distinguished from the split two piece formation of ordinary conveyer pole 45 jacketing), said sections are more highly resistive to distortion and strain notwithstanding unevenness or twist in the grain of the wood composing them, and therefore less likely to fracture incident to expansion and contraction. Moreover, 50 due to the circumferential insulating air spaces 20, the jacketing 16 is protected against heat which would otherwise be directly conducted to it from the metallic core member 15, with the result that deterioration of the jacket sections 55 17-19 from temperature changes is reduced to a minimum. The sectional construction of the jacketing 16 is further advantageous, since, in the event that any one of the sections 17-19 should, after long service, become distorted or 60 fractured to the extent of causing streaks or marks on the material hung on the pole, it can be readily replaced without requiring renewal of the jacketing 16 as a whole, maintenance costs being thereby very greatly reduced with corresponding increase in the efficiency of the drying machine.

In the modified form of pole shown in Fig. III, the spacing collars 23a are provided with lateral 70 annular flanges 32 to opposite sides of a central circumferential flange, said annular flanges constituting rests for the contiguous ends of adjacent jacket sections 17a, 18a and serving to maintain said sections coaxial with the core member 15a. The abutting ends of the jacket sections 17a and 75 18a, instead of being cut square as in Fig. I, are

complementarily beveled. If desired, the collar 23a may be internally notched like the collar 23 of Figs. I and II for the purposes of communication between the insulating air spaces 20a.

In the modification of Fig. IV, the external 5 diameter of the spacing collar 23b corresponds exactly to that of the jacket sections 17b and 18b; and said collar is formed with beveled recesses 34 in its opposite side faces, to receive the complementarily beveled ends of the jacket 10 sections 17b, 18b. In addition to holding the jacket sections 17b and 18b coaxial with the core member 15b with the insulating air spaces 20b intervening, the spacing collar 23b imposes restraint against circumferential expansion of the 15 ends of said sections.

While we have herein illustrated and described the several forms of our novel conveyer poles as being of circular cross section, obviously they can be made to polygonal cross section without 20 departing from the spirit of our invention. The term "cylindric" as used in the appended claims is therefore to be considered as comprehensive of any modifications of the cross sectional configuration of the poles. 25

Having thus described our invention, we claim:

1. A conveyer pole for drying machines and the like comprising a number of cylindric unitary sections of non-metallic material arranged end to end; interengaging collars uniting the several sections in axial alignment; and means to hold the sections assembled against endwise separation. 30

2. A conveyer pole for drying machines and the like comprising a number of cylindric sections 35 of non-metallic material arranged end to end; interengaging notched-collars at the junctures of the sections for determining axial alignment between them and for preventing relative rotation; and means to hold the sections assembled against endwise separation. 40

3. A conveyer pole for drying machines or the like comprising a number of cylindric sections of non-metallic material arranged end to end; 45 interengaging internally-grooved collars at the junctures of the sections determining axial alignment between them; and means cooperating with the endmost sections to hold the series assembled against separation. 50

4. A conveyer pole for drying machines or the like, comprising an axial core member; and a non-metallic jacket surrounding said core member with provision of a circumferential air-space, said jacket being composed of a number 55 of tubular sections arranged end to end and supported coaxially of the core member by longitudinally-grooved interengaging collars.

5. A conveyer pole for drying machines or the like comprising an axial core member; a non-metallic coaxial jacket surrounding the core member with position of an intervening circumferential air-space, said jacket being composed of a number of aligned tubular sections, said sections having an internal diameter larger than 60 the diameter of the core member, and collars having internal longitudinal grooves interengaging the section confronting ends. 65

6. A conveyer pole for drying machines or the like comprising an axial core member; a non-metallic jacket surrounding said core member with provision of a circumferential air-space, said jacket being composed of a number of tubular sections; and internally-grooved spacing 70 collars surrounding the core member and engag- 75

ing opposing annular recesses in the confronting ends of contiguous jacket sections.

7. A conveyer pole for drying machines or the like comprising an axial core member; a non-metallic jacket surrounding said core member with provision of a circumferential air-space, said jacket being composed of a number of tubular cylindric sections disposed end to end and having an internal diameter larger than the diameter of the core member; and spacing collars fitting the core member and engaging opposing recesses in the ends of contiguous jacket sections, said spacing collars having internal circumferential notches rendering the aforesaid air space continuous throughout the length of the pole.

8. A conveyer pole for drying machines and the like comprising an axial core member; a non-metallic cylindric jacket surrounding the core member; a collar secured to the core member adjacent one end thereof for abutment of the corresponding end of the jacket; a helical spring surrounding the core member within an axial hollow at the opposite end of the jacket, said spring being in compression between an annular shoulder of the hollow and another collar affixed to the core member, and operative to maintain the opposite end of the jacket in contact with the first mentioned collar.

9. A conveyer pole for drying machines and the like comprising an axial core member; a non-metallic cylindric jacket surrounding the core member and composed of a number of serially arranged tubular sections; an abutment collar for one of the end-most jacket sections fixed to

the core member at the corresponding end thereof; a helical spring surrounding the core member within an axial end hollow in the other end-most jacket section of the series, said spring being in compression between an annular shoulder of the hollow and another collar affixed to the core member and operative to maintain the jacket sections closely engaged with each other and with the collar first mentioned.

10. A conveyer pole for drying machines and the like comprising a number of cylindric sections of non-metallic material arranged end to end; interengaging collars at the junctures of the sections determining axial alignment between them; and an axial member with adjustable means to hold the sections assembled against endwise separation, said means also serving to set apart journal sections at opposite ends of the pole.

11. A conveyer pole for drying machines and the like comprising a number of tubular one-piece sections of non-metallic material arranged end to end; interengaging internally-grooved collars at the junctures of the sections determining axial alignment between them; a tubular axial member with adjustable collars to hold the sections against endwise separation and also set apart terminal sections of the roll at its opposite ends as journals therefor; and one of the collars at one end of the pole embodying a gear means for rotating said pole.
